UNITED STATES PATENT OFFICE.

CHRISTIAN IMANDT, OF NEW YORK, N. Y.

METHOD OF REFINISHING CURTAINS.

SPECIFICATION forming part of Letters Patent No. 404,543, dated June 4, 1889.

Application filed January 22, 1889. Serial No. 297,208. (No specimens.)

To all whom it may concern.

Be it known that I, CHRISTIAN IMANDT, of the city, county, and State of New York, a citizen of the United States, have invented 5 certain new and useful Improvements in the Method of Refinishing Curtains, of which the following is a specification.

This invention relates to an improved method of refinishing lace curtains in a quick and 10 effective manner without injury to the curtains and without requiring the use of large cumbrous stretching-frames; and the invention consists of a method of refinishing curtains, composed of the following successive 15 steps: first, basting a number of superposed curtains together at the edges; secondly, washing the so-basted curtains; thirdly, drying the same; fourthly, sizing them, and, lastly, stretching and again drying the same. 20 In carrying out my improved process of refinishing curtains a number of curtains of the same size are laid one on top of the other and basted together along the four edges. The so-basted curtains are then carefully washed, 25 care being taken that they are not torn in washing. They are then dried by natural or artificial heat and sized in the usual manner. They are then applied to a stretching-frame consisting of narrow, flat, or round strips of 30 metal, which are passed through the curtains along the basted edges of the same, so that the metal strips extend beyond the corners of the curtains and cross each other at those points. To the stretching-strips are applied, 35 at the corners and at points midway of their longer side strips, suitable stretching-tackle, by which the stretching-strips are drawn in outward direction, whereby the curtains are tightly stretched ready for the drying action. 40 By the contact of the curtains with each other and the yielding stretching action in which

they are exposed the curtains are not liable to break at any part, as one curtain sustains the other and as the basting of the edges is strong enough to resist the stretching strain 45 on the curtains.

The essential point of novelty of my improved method of repairing lace-curtains consists in basting the curtains together at the edges, as the remaining steps are old and well 50 known.

The advantages of my improved process are, first, that any desired number of curtains, provided they are of the same size, can be refinishing together without requiring the cumbrous stretching-frames heretofore in use; 55 secondly, that the curtains are less injured in refinishing than when finished singly and separately, as the superimposing of a number of curtains, basting them, and stretching them 60 while so basted together exerts a less injurious strain on each individual curtain; thirdly, that the curtains can be refinishing in a quicker manner and at less expense than by the former method. 65

Having thus described my invention, I claim as new and desire to secure by Letters Patent—

The method herein described of refinishing lace curtains, which consists, first, in connecting a number of superposed curtains by basting their edges together; secondly, washing the so-basted curtains; thirdly, drying the same; fourthly, sizing the dried curtains, and, lastly, stretching and drying the same, substantially as set forth. 75

In testimony that I claim the foregoing as my invention I have signed my name in presence of two subscribing witnesses.

CHRISTIAN IMANDT.
